FIBROUS SCOURING PADS AND PROCESS FOR THE PREPARATION THEREOF

John Donald Zilinskas, Jackson Heights, N.Y., assignor to Colgate-Palmolive Company, New York, N.Y., a corporation of Delaware

Filed Dec. 10, 1956, Ser. No. 627,202

6 Claims. (Cl. 15—209)

The present invention relates to fibrous scouring pads. More particularly it relates to fibrous scouring pads of triangular shape and a method for the preparation thereof from a strip of substantially parallel loosely intertwined fibers.

Steel wool scouring pads have previously been prepared by folding or rolling up, along its longitudinal axis, a strip of steel wool in which the fibers run substantially parallel to said axis. The fibers which form the strip are held together laterally simply by some slight intertwining thereof and as a result of the tendency of the rough and uneven surfaces of the fibers to snag on each other. Naturally, pads prepared by merely rolling up such a strip have little lateral tensile strength, and in use tend to rapidly fall apart. This problem has previously been recognized and attempts have been made to overcome it by the use of wire mesh or sewn or woven fibrous materials for making scouring pads, however the required weaving or manipulations add substantially to the cost of the pads.

The present process constitutes an economical method for preparing scouring pads from a strip of steel wool in which the fibers run substantially parallel to the major axis of the strip. Pads produced by the present process are composed of superposed layers of steel wool, the fibers in each layer running perpendicular to the fibers in each adjacent layer. This 90° cross-netting gives superior mechanical strength to the pad.

Pads produced by the instant process are triangular in shape. Thus, they are easily used in the manner of conventional square or round pads, but also, by virtue of their acute corners, may be used to reach and clean inner corners and crevices of soiled utensils in a highly effective manner.

Furthermore, the triangular pads produced according to the instant process are easily packaged two to a layer, in boxes of square cross section.

It is characteristic of pads prepared according to one embodiment of the present invention that they may, after usage, be opened and reversed so as to make available to the user fresh, unused inner fibers.

In accordance with the present invention a triangular scouring pad comprises a plurality of superposed triangular segments of a strip of loosely intertwined fibers. Also part of the present invention is a process for preparing such a triangular shaped scouring pad from a strip of substantially parallel loosely intertwined fibers, said fibers being oriented along the major axis of said strip, which process comprises repeatedly folding a corner of said strip sequentially obliquely at 45° and perpendicularly to said major axis, so as to produce a triangular layered pad in which the fibers of the successive layers run perpendicular to each other.

In the drawings:

Fig. 1 illustrates a face of a rectangular strip of fibers wherein the fibers are oriented substantially parallel to the major axis of the strip,

Figs. 2 to 8 illustrate successive steps in a preferred embodiment of the present novel folding process, and

Figs. 9 through 13 illustrate successive steps in an alternative embodiment of the present invention.

- 5 Referring now to Fig. 2, a corner 10 is folded over against the exposed face 11 of the strip along a fold line 12, 14 bisecting, at 45°, the corner 14 nearest the folded corner 10. This fold also crosses the major axis A—A of the strip obliquely at 45°.
- 10 A second step in the instant embodiment involves inwardly doubling over the already folded corner 12—14—16 against the exposed face of the strip 11 along a perpendicular 12—16 to the major axis A—A, thus forming a layered triangular corner 12—16—18. (The perpendicular 15 12—16 lies adjacent to and immediately under a leg of the triangularly folded corner 12—14—16, as illustrated in Figs. 2 and 3.) A third fold, illustrated in Fig. 4, is performed along the diagonal 12—18 which lies under the base of the previously formed triangular corner 12—16—18, thus 20 forming a new layered triangular corner 12—18—20. As illustrated in Fig. 5 the next step consists of doubling over, again against the exposed face 11 of the original strip, the triangular corner 12—18—20 formed in the preceding step. Doubling over of the folded corner against the exposed face of the strip along the edges (18—22, 22—24 and 22—26) of the triangular fold adjoining the remaining portion of the exposed face of the strip is continued as illustrated in Figs. 6, 7 and 8 until finally a triangular layered pad 22—26—28 in which the fibers of the successive 25 30 layers run perpendicularly to each other is produced, as in Fig. 8.

A second embodiment of the present invention is illustrated in Figs. 9—13, Fig. 9 illustrating an exposed face 40 of a suitable starting strip of fibers. The fibers of the strip are oriented substantially parallel to the major axis A—A thereof. The strip is rectangular in shape and has a length which is a simple multiple of its width, e.g. about 4 times.

- 35 As shown by Fig. 10, the instant embodiment comprises folding two corners 52 and 82 common to one of the longer edges of the strip inwardly against the exposed face 40 thereof along diagonals 54—56 and 84—86 bisecting at 45° the remaining two corners 54 and 84. Each originally folded, now triangular shaped corner 40 45 54—56—58 and 84—86—88 of the strip is further repeatedly folded against the initially exposed face 40 of the strip along the edges 56—58, 56—70 and 86—88; 86—70 of the successively formed triangular folds adjoining, in each instance, the remaining portion of the initially exposed 50 55 face of the strip until finally an isosceles right triangular layered structure 56—70—86 is produced as in Fig. 12. As shown by Figs. 11 and 12, an equal number of folds are made on each half of the initial strip, so that the minor axis B—B of the initial strip bisects the right angle 70 of the isosceles triangular layered structure so produced.

This structure 56—70—86 of Fig. 12 is then doubled over along the centerline B—B to form the ultimate pad, as illustrated in Fig. 13. After usage the consumer may open and reverse the pad as illustrated in Fig. 13 along 60 the axis B—B, and thereby obtain a fresh unused working surface.

After the present pads have been formed, they may be stamped or crimped along the edges so as to help them retain their shape and prevent unravelling.

- 65 Although the instant invention has been described with reference to particular embodiments thereof, it will be apparent to those skilled in the art that variations and modifications can be made. Thus, it is obvious that the illustrated sequence of folding can be changed considerably and yet produce the same final structure. Also although the instant disclosure relates to the preparation 70

of pads from strips having a length of about four times their width, it is apparent that other multiples may be involved, i.e. three, five, six, eight and so forth. The present scouring pads may be fabricated with any number of layers from strips of any fibrous material (e.g. metals, plastics, vegetable fibers, etc.) wherein the fibers are oriented substantially parallel to the length of the strip, and may be impregnated, before or after manufacture, with soap or any other desired agent.

What is claimed is:

1. A process for preparing a scouring pad of triangular shape from an elongated rectangular strip of substantially parallel loosely intertwined fibers, said fibers being oriented along the major axis of said strip, comprising doubling over against one face of said strip, two corners of said rectangular strip, said folds bisecting the remaining corners of said strip, further folding over said doubled corners against said face of said strip along perpendiculars to the major axis thereof so as to envelop at least part of the edges of said strip and form a shortened rectangular strip having two multilayered triangular corners, folding over said multilayered triangular corners along the hypotenuse thereof and against said face of said strip to form an isosceles right triangle, and doubling over said isosceles right triangle along a line bisecting the right angle thereof and having a length equal to the width of said strip.

2. A process for preparing a scouring pad of triangular shape from an elongated rectangular strip of substantially parallel loosely intertwined fibers, said fibers being oriented along the major axis of said strip, comprising doubling over against one face of said strip, two adjacent corners of one of the longer edges of said rectangular strip, said folds bisecting the remaining corners of said strip, further folding over said doubled corners against said face of said strip along perpendiculars to the major axis thereof so as to envelope at least part of the edges of said strip and form a shortened rectangular strip hav-

ing two multilayered triangular corners, folding over said multilayered triangular corners along the hypotenuse thereof and against said face of said strip to form an isosceles right triangle, and doubling over said isosceles right triangle a line bisecting the right angle thereof and having a length equal to the width of said strip.

3. A process for preparing a scouring pad of triangular shape as set forth in claim 2 wherein the length of said rectangular strip is about four times its width.

10 4. A triangular scouring pad which comprises a plurality of superposed interconnected triangular segments of an elongated rectangular strip of substantially parallel loosely intertwined fibers, the fibers in each of said segments running substantially parallel to each other and substantially perpendicular to the fibers of a segment adjacent thereto, each of said triangular segments having a side in common with the periphery of said rectangular strip, and the exposed outermost triangular segments of said pad being joined to each other along a common edge thereof to envelop therebetween a plurality of interiorly disposed segments and the periphery of said rectangular strip associated therewith.

15 5. A triangular scouring pad as set forth in claim 4 wherein the fibers in each of said segments run parallel to each other and substantially perpendicular to the fibers of each segment adjacent thereto.

20 6. A triangular scouring pad as set forth in claim 4 having an altitude equal to the width of said strip.
